US00D853994S

(12) **United States Design Patent** (10) **Patent No.:** **US D853,994 S**
Lin (45) **Date of Patent:** **** Jul. 16, 2019**

(54) **WIRELESS EARPHONE**

(71) Applicant: **SHENZHEN DACOM ELECTRONICS CO., LTD.**, Shenzhen (CN)

(72) Inventor: **Chuqiang Lin**, Shenzhen (CN)

(73) Assignee: **SHENZHEN DACOM ELECTRONICS CO., LTD.**, Shenzhen (CN)

(**) Term: **15 Years**

(21) Appl. No.: **29/633,671**

(22) Filed: **Jan. 15, 2018**

(30) **Foreign Application Priority Data**

Jul. 18, 2017 (CN) 2017 3 0317800

(51) **LOC (11) Cl.** **14-01**

(52) **U.S. Cl.**

USPC **D14/223**

(58) **Field of Classification Search**

USPC D14/223, 205, 188, 192, 150, 155, 156, D14/137, 160, 167, 191; 181/129, 130, 181/135; 379/430, 431; 381/380, 381, 381/374; 455/90, 3, 575.1, 569.1

CPC H04R 1/10; H04R 25/00; H04R 1/1016; H04R 1/1066; H04R 5/033; H04R 5/0335; H04R 1/105

See application file for complete search history.

(74) *Attorney, Agent, or Firm* — Peter J. Ims; Westman, Champkin & Koehler, P.A.

(57) **CLAIM**

The ornamental design for wireless earphone, as shown and described.

DESCRIPTION

FIG. 1 is a perspective view of a wireless earphone; FIG. 2 is a front view of the wireless earphone; FIG. 3 is a back view of the wireless earphone; FIG. 4 is a left view of the wireless earphone; FIG. 5 is a right side view of the wireless earphone; FIG. 6 is a top side view of the wireless earphone; and, FIG. 7 is a bottom view of the wireless earphone.

The broken lines shown in the drawings disclosure are for illustrative purposes only and form no part of the claimed design.

1 Claim, 7 Drawing Sheets
